UNITED STATES PATENT OFFICE.

FRED HASKELL SMITH, OF BLOOMFIELD, NEW JERSEY.

DESIGN FOR A TIRE.

57,790.

Specification for Design.

Patented May 3, 1921.

Application filed September 18, 1920. Serial No. 411,330. Term of patent 14 years.

To all whom it may concern:

Be it known that I, FRED HASKELL SMITH, a citizen of the United States, residing at 175 Berkeley avenue, in the city of Bloomfield, county of Essex, State of New Jersey, have invented a new, original, and ornamental Design for Tires, of which the following is a specification, reference being had to the accompanying drawing, forming part thereof.

Figure 1 is a transverse sectional view taken on the line 1—1 of Fig. 2;

Fig. 2 is a fragmentary plan view of a tire tread embodying my design.

I claim—

The ornamental design for a tire as shown.

FRED HASKELL SMITH.
